MOVABLE HEATER FOR USE WITH
PORTABLE TANKSJames L. Breese, Santa Fe, N. Mex., assignor, by
mesne assignments, to Breese Burners, Inc.,
Santa Fe, N. Mex., a corporation of Delaware

Application March 15, 1944, Serial No. 526,506

6 Claims. (Cl. 158—91)

1

My invention relates to an improvement in liquid fuel burners and has for one purpose to provide a burner which may be applied to portable fuel tanks of the type which are employed in conveying liquid fuel for military purposes and which are frequently called "blitz tanks." Another purpose is to provide a burner which may be easily and quickly applied to such tank and may be efficiently locked in place and quickly removed. Another purpose is to provide a burner including means to supply air to the "blitz tank" to assist in the vaporization of the fuel therein and to assist in the conveyance of the vaporized fuel to the burner. Another purpose is to provide a combustion chamber which may be immediately applied to and thereabout an immediate connection with the tank. Other purposes will appear from time to time in the course of the specification. Whereas I show my invention as applied to a so-called "blitz tank," it will be understood that any suitable and preferably portable fuel tank may be employed.

I illustrate the invention more or less diagrammatically in the accompanying drawings, wherein:

Figure 1 is a vertical section with parts in side elevation;

Figure 2 is a section on the line 2—2 of Figure 1;

Figure 3 is a section on the line 3—3 of Figure 1;

Figure 4 is a section on the line 4—4 of Figure 1;

Figure 5 is a partial vertical section on an enlarged scale; and

Figure 6 is a side elevation on a somewhat enlarged scale of part of the structure shown in Figure 5, as seen from the line 6—6 of Figure 1.

Like parts are indicated by like symbols throughout the specification and drawings.

Referring to the drawings, I generally indicate a so-called "blitz tank" having a carrying handle including three tubular members 2 and connecting securing abutments 3, 4 at the ends thereof. The top of the tank is more or less irregularly formed and includes a portion 5 spaced downwardly below the handle tubes 2 and an inclined portion 6 apertured as at 7 and having an abutment ring 8 internally screw threaded as at 9 to receive any suitable removable screw threaded cap 10 permanently secured to the tank, for example by a chain 11. The burner assembly includes a burner pot 12 having therein a plurality of primary air inlets 13 circumferentially spaced thereabout and located at various distances from

2

the bottom. The pot has a bottom 14 apertured as at 15. Secured to the pot bottom is the tubular member 16 which has a lower portion of reduced diameter 17 which extends through the sleeve 8 and terminates in a ledge 18 which abuts against the sleeve 8. Outwardly extending from one side of the pot 12 is an arm 19 which is in part cylindrically formed as at 20 to conform to the exterior of the center handle tube 2. One side of the cylindrical portion 20 is downwardly extended as at 21 and is provided with a laterally extending flange 22 to which is rotatably secured a locking member 23 shown as having a downwardly turned outer end 24. 25 is a lug extending downwardly from the opposite side of the cylindrical portion 20. It is provided with a notch 26, for receiving the shank of the securing member 23. It will be understood that when the member 20 is placed in the position in which it is shown in Figures 1 and 5 the locking member 23 may then be swung into the position in which it is shown in Figures 3 and 5, engaging the notch 26 and the bottom of the handle tube 2. This is done when the sleeve 17 has been inserted in the position as shown in Figure 5, and the result is to lock the burner assembly firmly in position in relation to the blitz tank with the interior of the pot 12 in communication with the interior of the blitz tank. A row of secondary air inlet apertures is shown adjacent 30 to the top of the pot 12 as at 30. 31 is a centrally apertured flame ring. 32 is an outer skirt open at the bottom as at 33 and cut away as at 34 to permit the passage of the member 19. It may be rolled inwardly above the outer flange 12—a of the pot 12, as at 35 and serves to center the flame ring 31 in relation to the pot. It is rolled outwardly as at 36 and inwardly again as at 37 to terminate in an upwardly extending generally cylindrical sleeve 38. 39 is a generally cylindrical 40 stove or heat radiating member which may be slipped on the sleeve 38 and abuts downwardly against the outward bead 36. A cover cap 40 may be positioned at the top, abutting for example against a bead 41. The cap 40 may carry a top portion 42 which in turn carries a sleeve 43 about which any suitable flue extension 44 may be slipped. All the parts can be readily disassociated from each other to take the entire burner down, as only a slip fit is employed.

Extending downwardly into the blitz tank is an air inlet tube 50 which is provided with a plurality of longitudinal slots 51. The tube 50 has an outwardly extending elbow 52 at its upper end which extends outwardly through an aperture 53 in the passage member 16 and terminates

with an upper end 54 in communication with the atmosphere. It will be observed that the tube 50 is shown as extending to and resting on the bottom of the blitz tank. The longitudinal slots 51 provide air inlet spaces extending substantially from top to bottom of the blitz tank. For strength the slots may be separated by sections 51a. 60 is an air controlling shutter provided with a sleeve 61 slidable and rotatable on a pivot pin 62, the pivot pin being secured to a ring 63 which may be locked about the L 52, for example by the screw 64. The pin 62 carries an abutment washer 65 the spring 66 being compressed between the abutment and the face of the shutter 60. The shutter may be provided with an actuating handle 68 and is so formed that when at one limit of its movement it entirely closes the otherwise open end of the L 52 while at the other end of its movement it leaves the open end 54 entirely open. It constitutes the only adjustable control means for controlling the burner.

What I provide is in essence a generator type burner in which the rate of combustion is controlled by controlling the rate of flow of air to the body of fuel.

It will be realized that whereas I have described and shown a practical and operative device, nevertheless many changes may be made in size, shape, number and disposition of parts without departing from the spirit of my invention. I, therefore, wish my drawings and description to be taken as in a broad sense illustrative and diagrammatic.

The use and operation of my invention are as follows:

I illustrate a generator type burner which may advantageously be used in connection with containers in which liquid fuel is handled or shipped. I illustrate my invention as applied to the so-called "blitz tank" which is used to carry liquid fuel for Army use. However, my invention may be applied readily to other types of container, with little or no modification of structure.

In the structure as shown I illustrate a readily demountable burner and heater structure which can be applied to a "blitz tank" without any modification of the structure of the tank. It may be readily applied to and removed from the tank. By merely releasing the locking lever 23, it is possible to lift the burner assembly bodily from the tank. The burner assembly may be taken down by removing the flue structure from the stove and the stove from the burner. Thus it can be packed into a small bulk for shipment.

In the use of the burner, the air for combustion is supplied to the pot through the apertures 13 and 30. The pot is of the so-called "hydroxylating" type. In order to provide a supply of fuel to the pot for mixture with the air which flows through the primary apertures 13 and the secondary apertures 30, I introduce some air into the "blitz tank" and maintain a limited initial combustion effective to vaporize some of the liquid fuel. This vaporized but unburned liquid fuel moves upwardly through the neck 16 into the interior of the pot 12. It is there mixed with the primary air flowing in through the apertures 13. The mixture thus formed then receives the secondary air through the apertures 30. This final mixture then burns at or above the level of the top of the pot. The tube 50 with its slots 51 is effective to supply the relatively small amount of air necessary to maintain the limited combustion within the tank. The rate of inflow of this air, and thus the rate of combustion within the

tank can be controlled by manipulating the valve 69. The greater the volume of air admitted, the greater will be the amount of vaporization taking place in the tank, and the hotter the fire in the pot above the tank.

I claim:

1. In combination with a portable liquid fuel tank having an access aperture in the top of the tank, a burner assembly and means for removably securing it to said tank, said assembly including a burner pot, a passage member extending from the bottom of said pot to the access aperture of the tank, an air inlet tube extending to the interior of said tank through said passage member, means for controlling the rate of flow of air into said tank through said tube, and a radiating member mounted on said burner pot, the interior of said radiating member being in communication with the interior of the pot, said pot having a plurality of air inlet apertures located at various levels therein, and a centrally apertured flame ring at the top of the pot, and between the pot and the radiating member.

2. In combination with a portable liquid fuel

25 tank having an access aperture in the top of the tank, a burner assembly and means for removably securing it to said tank, said assembly including an open ended burner pot, a passage member extending from the bottom of said pot to the access aperture of the tank, an air inlet tube extending to the interior of said tank through said passage member, means for controlling the rate of flow of air into said tank through said tube, said pot having a circumferential side wall and a plurality of air inlet apertures located at various distances from the open 30 end of said pot and spaced circumferentially around said wall and a centrally apertured flame ring partly closing the upper open end of the pot.

3. In combination with a portable liquid fuel tank having an access aperture in the top of the tank, and a handle on the top of the tank, adjacent said aperture, a burner assembly and means for removably securing it to said handle, said assembly including a burner pot, a passage member extending from the bottom of said pot to the access aperture of the tank, an air inlet tube extending to the interior of said tank through said passage member, means for controlling the rate of flow of air into said tank through said tube, and a radiating member mounted on said burner pot, the interior of said radiating member being in communication with the interior of the pot, said pot having a plurality of air inlet apertures located at various levels therein, and a centrally apertured flame ring at the top of the pot, and between the pot and the radiating member.

4. In combination with a portable liquid fuel 45 tank having an access aperture in the top of the tank, and a handle adjacent said aperture, a burner assembly and means for removably securing it to said handle, said assembly including a burner pot having a circumferential side wall, an open end and a partially closed end, a passage member extending from the partially closed end of said pot to the access aperture of the tank, an air inlet tube extending to the interior of said tank through said passage member, and means for controlling the rate of flow of air into said tank through said tube, the circumferential side wall of said pot having a plurality of air inlet apertures spaced circumferentially thereabout and located at various distances from 50 the ends of the pot.

5. In combination with a portable liquid fuel tank having an access aperture in the top of the tank, a burner assembly and means for removably securing it to said tank, said assembly including a burner pot having a circumferential side wall, an open end and a partially closed end, a passage member extending from the partially closed end of said pot to the access aperture of the tank, an air inlet tube extending to the interior of said tank through said passage member, and means for controlling the rate of flow of air into said tank through said tube, the circumferential side wall of said pot having a plurality of air inlet apertures spaced circumferentially thereabout and located at various distances from the ends of the pot.

6. In combination with a portable liquid fuel tank having an access aperture in the top of the tank, a burner assembly and means for removably securing it to said tank, said assembly including a burner pot having a circumferential side wall, an open end and a partially closed end, a passage member extending from the partially closed end of said pot to the access aperture of the tank, an air inlet tube extending to the interior of said tank through said passage member, and means for controlling the rate of flow of air into said tank through said tube, the circumferential side wall of said pot having a

plurality of air inlet apertures spaced circumferentially thereabout and located at various distances from the ends of the pot, said air inlet tube including a lower portion located within and generally parallel with the passage member extending from the partially closed end of the pot to the access aperture of the tank, and a top portion extending angularly from said lower portion and outwardly through said passage member.
